Primary Examiner — Ian Simmons*Assistant Examiner* — Carissa C Fitts(74) *Attorney, Agent, or Firm* — Brooks Kushman P.C.(57) **CLAIM**

The ornamental design for a capo, as shown and described.

DESCRIPTION

FIG. 1 is a perspective view of a capo showing my new design;

FIG. 2 is a left side elevational view thereof;

FIG. 3 is a front elevational view thereof;

FIG. 4 is a rear elevational view thereof;

FIG. 5 is a top plan view thereof; and,

FIG. 6 is a bottom plan view of the present invention.

The broken lines represent unclaimed portions of the design and form no part of the claimed design.

1 Claim, 4 Drawing Sheets(56)
